UNITED STATES PATENT OFFICE.

HOWARD G. SHORTT, OF CARTHAGE, NEW YORK, ASSIGNOR OF ONE-HALF TO STEBBINS
ENGINEERING AND MANUFACTURING COMPANY, OF WATERTOWN, NEW YORK, A
CORPORATION OF NEW YORK.

AUTOMATIC RECEIVER PUMP.

Application filed April 8, 1927. Serial No. 181,950.

This invention refers to an automatic receiver pump, designed chiefly for handling high temperature condensate, boiler feed water, and the like, it being adapted for use with air, steam, water, gas, and all other kinds of gases, fluids, and liquids; and in fact it is intended to be utilized for handling any kind of fluid or liquid or other similar substance or material; as, for example, the device may serve in connection with a steam condensation plant, or a hot water heating system, or a water distribution apparatus, or any other apparatus, mechanism or system having a similar purpose.

The present improvements relate more particularly to that class of pumps or automatic receivers exemplified in the fluid pressure alternating mechanism patented by me with Alderic Cormier, July 28, 1925, No. 1,547,830; and the automatic receiver pump described and claimed in my former application for Letters Patent filed Nov. 18, 1926, Serial Number 149,159; my present improved mechanism involving various improved features upon the devices covered by said patent and application.

The present novel improvements are applied in connection with a single receiver, tank, or reservoir, instead of a plurality of receivers or reservoirs, as in the Letters Patent referred to; and instead of a pair of control valves for the control piston which actuates the high pressure steam and vent valves of the receiver, as in my application referred to, I use a single control valve for the piston and its cylinder, the same being of a balanced and hollow piston type to control the pressure and exhaust to and from both ends of the control cylinder and both sides of the control piston therein. And moreover the present invention includes a novel and ingenious disposition and construction of the steam and vent valves for the receiver; together with automatic devices in the receiver actuated by the level of the water therein for operating the pressure-control valve and causing it through the medium of the control piston and levers to positively open and close the steam and exhaust valves, so that the receiver may be discharged of its aqueous contents when full by introducing steam or pressure, and may be relieved of such steam or pressure when emptied of its aqueous contents so that it can immediately fill up again,

in automatic alternation; and the invention 55 may also be said to consist, moreover, in the numerous details and peculiarities in the construction, combination, and arrangement of the various parts, substantially as will be hereinafter described and claimed. 60

In the accompanying drawing illustrating my invention:

Figure 1 is a front elevation of my improved automatic receiver pump.

Figure 2 is a vertical section of the same 65 through the valve devices in a plane parallel to the head of the receiver.

Figure 3 is a vertical central cross-section of the valve devices and proximate parts at right angles to the sectional view in Figure 70 2, certain parts being in side view.

Figure 4 is a detail sectional view of the vent valve on the line 4, 4, of Figure 2.

Figure 5 is a detail sectional view of the steam valve on the line 5, 5, of Figure 2. 75

Figure 6 is an inside face view on a reduced scale of the receiver head, showing particularly the steam supply and exhaust passage for the receiver.

Figure 7 is a horizontal sectional plan 80 view of the control piston and its cylinder, and shows contiguous thereto in cross-section the single operating valve which actuates the control piston and cylinder.

Figure 8 is a sectional side elevation on the 85 line 8, 8, of Figure 7.

Figure 9 is a vertical section on the line 9, 9, of Figure 7.

Figures 10 and 11 are sectional views similar to Figure 9 of a modified form of the 90 pressure valve.

Similar characters of reference designate corresponding parts throughout all the different figures of the drawing.

In the present specimen or example of the 95 invention, as delineated for explanatory purposes, A denotes a tank, receiver, or reservoir, which may be of any size, shape, and design, and may be considered for example as arranged with a steam condensation plant. 100 The condensation water flows into the tank through the opening a, and at the proper time when the tank is full the water is discharged from the tank through the same opening a. This automatic pumping of the receiver is accomplished through the agency 105 of high pressure steam which enters the top of tank A through an inlet port F after

the tank has completely filled up with water. The introduction of steam pressure against the water when the tank is full has the function of expelling the water, and after this is done the steam is vented to atmosphere or elsewhere through the same port F, so that the tank A will be at liberty to refill again with water. Tank A has a removable tank head B bolted thereto by bolts b, and formed on the face nearest the tank with an elongated steam supply port D having an inlet port d through which a steam supply valve introduces steam to the supply port D; and the head B is also formed with an elongated discharge or vent port C for the steam after it is used, the same having an outlet port c through which the steam enters the steam vent valve. The ports C and D merge together in the union port E which connects them both with the receiver port F through which at one time live steam from port D enters the receiver and at another time the steam is allowed to escape into vent port C, all as I shall presently describe in detail. When steam enters port D to fill the receiver it will also fill port C and be ready to vent through vent valve after the supply valve closes.

I will first describe the valves which admit live or high pressure steam to the receiver when it is full of water and dispose of such steam when the receiver is empty of water after its ejection, said valves being quite similar in construction. The steam admission valve is supported at the right on receiver head B and is shown so placed in Figures 1 and 2, and in detail in Figure 5; and the steam vent valve is supported at the left on receiver head B and is shown so placed in Figures 1 and 2, and in detail in Figure 4.

The steam inlet valve has a casing 11 that is bolted or otherwise secured to head B. Within casing 11 is the vertically-movable valve 13, whose lower inclined end 25 plays back and forth with relation to its seat 14 and controls communication between the inner chamber 19 and the outlet port d in passage D. A pipe nozzle 31 on the valve casing 11 allows connection with a pipe conveying high pressure steam from the boiler or some other point in the steam line to the chamber 19 on one side of valve 13, from which the valve when open delivers steam to port d and passage D to the reservoir. Valve casing 11 has a cover 12 bolted thereon and fashioned with a bearing for the valve stem 15, which is suitably packed where it emerges from its bearing, a screw cap 23 being used to make a tight joint over this packing. While there is a chamber 19 in casing 11 below valve 13, which is constantly filled with live steam, there is also a chamber 32 in casing 11 above valve 13, and valve 13 is a loose fit so that steam may pass from

chamber 19 to chamber 32. This looseness is slight and is usually obtained by leaving out the packing rings on the valve. Further, the valve stem 15 which passes through the valve 13 has a winged section 17 which functions in the passage in valve 13, there being a relief valve 16 on stem 15 at the upper end of the winged section 17 and adapted to close the passage in valve 13 when the valve 13 is seated on its seat 14, and also the winged section 17 projects at times below the lower end of passage in valve 13 and carries a perforated disc or block 18 that contacts against the lower end of valve 13, when valve stem 15 is lifted, the disc at this time being received into a cavity in the valve 13 inside of valve flange 25. Hence in the operation of the stem 15 in moving the valve 13 it will be seen that when valve flange 25 is closed down on seat 14, at which time live steam is cut off, the relief valve 16 is also closed, but at this time steam can pass around valve 13 from chamber 19 to chamber 32, but when the stem 15 is raised it will first open relief valve 16 before the valve disc 18 lifts on valve 13 and before valve 13 is lifted from seat, and the steam in chamber 32 above valve 13 will find relief through the passage along between the wings of winged section 17, and through perforated block 18, into chamber 19, where the valve 13 will be lifted from its seat by this escaping pressure, the area of valve 13 below being greater than that of valve 16.

The steam vent or exhaust valve for the escape of steam from the receiver after it has done its work therein of ejecting the contents is quite similar in most respects to the steam supply valve just described. It has a casing 11^a, in which is the valve 13^a, above which is a chamber 32^a, and below which is a chamber 19^a. While the steam chamber 19 receives live steam from steam pipe at 31, the chamber 19^a connects through port c with the long port C, so that the widest part of valve 13^a is thus exposed loosely to steam which passes around it and enters chamber 32^a from chamber 19^a. Casing 11^a is provided with a nozzle 31^a to which is coupled a pipe for carrying off the exhaust or vented steam, after the valve is opened to allow a discharge of this steam from port c into and through the valve to nozzle 31^a. Valve 13^a has a central passage, a lower valve flange 25^a surrounding a recess in the valve, and in the casing is a seat 14^a between the outlet chamber 19^a and the port c. The casing 11^a has a cover 12^a bolted thereon and providing a bearing for the valve stem 15^a which is suitably packed where it emerges from this bearing, and a screw cap 23^a is used to protect this packing and make a tight joint. The stem 15^a for the vent valve has a winged section 17^a which functions in

the central passage in valve 13^a, and at the upper end of section 17^a is a relief valve 16^a which at times closes on a valve seat at the upper end of the central passage in valve 13^a, 5 while the lower end of the winged section carries a disc or block valve 18^a that closes at times the lower end of the passage through valve body 13^a. The valve flange 25^a on the lower end of valve 13^a seats at 10 times on the seat 14^a, and also at times rises therefrom to let the steam vent out past seat 14^a into the escape nozzle 31^a and its connections. All these parts operate in discharging the steam in a manner analogous 15 to the similar parts of the steam inlet valve in admitting steam. And the function of the relief valve 16^a is similar to that of the relief valve 16. It will be noted that the steam inlet valve closes tightly before the 20 steam outlet valve opens, and conversely.

The upper end of the inlet valve stem 15 has a recess 20 containing at the end thereof a projecting pin 21 which is normally pressed outwardly by a spring 22; and the discharge valve stem 15^a has a similar recess 20^a containing at the end thereof a projecting pin 21^a which is normally pressed outwardly by a spring 22^a. The outer end of stem 15 beyond recess 20 is slotted at 24 to 25 receive the end of one arm of a bell crank lever 26, the end of which arm is rounded or carries an anti-friction roller 30 which bears against the end of the yielding pin 21; and similarly the end of stem 15^a beyond the recess 20^a is slotted at 24^a to receive the end of one arm of a bell-crank lever 26^a, the end of which arm is rounded or carries an anti-friction roller 30^a which bears against the end of the yielding pin 21^a. These two bell 30 levers 26 and 26^a actuate the two valve stems and positively open and close the inlet and outlet valves, opening one at the same time the other is closed, and the spring devices allow the control piston to make its 35 full travel without putting any extra or damaging strain on the valve seats.

I come now to describe the control piston and its cylinder and cooperating parts for operating the steam inlet and outlet valves 40 I have just described. Figure 7 represents these parts very clearly. I denotes a cylinder, which is secured to the receiver head B by suitable bolts or other means as shown in Figure 3. In the cylinder 1 is a piston 2, having a rod 4 extending in one direction and a rod 4^a extending in the opposite direction. Within the cylinder 1, at one side of the piston 2 is a pressure chamber 3 for receiving air or other pressure to propel the piston in one direction, and at the other side of piston 2 is another pressure chamber 3^a for receiving air or other pressure to propel the piston in the opposite direction. Piston rod 4 passes from cylinder 1 through a bearing 5, and its end is furnished with a pin 29^a

that is engaged by a hook 28^a on the end of one arm of a bell crank lever 26^a whose other arm carries the terminal 30^a which operates the stem of the vent valve, said bell crank lever being pivoted at 27^a on the head B. Likewise the piston rod 4 passes through a bearing 5^a on cylinder 1, and its end is provided with a pin 29 that is engaged by a hook 28 on the end of one arm of a bell crank lever 26, whose other arm carries a round terminal 30 which operates the stem of the steam inlet valve, as already described, said bell crank lever 26 being pivoted at 27 on head B. Through these connections therefore it will be seen how the control 80 cylinder 1 and the control piston 2 therein positively open and close the steam inlet and vent valves.

In front of the control cylinder 1 is a single vertical valve which functions as a cylinder control valve and controls the pressure and exhaust to and from both ends of the cylinder 1. This cylinder control valve is shown in detail in Figures 7, 8, and 9, and its position in relation to all the other parts, 85 as well as the method of its support is fully seen in Figures 1, 2, and 3. It comprises a cylindrical casing 6, provided with an upper head 53, consisting of a screw plug, and a lower head consisting of a screw plug 55, 90 which forms a bearing for the vertically-movable valve rod 9, which is properly packed to prevent leakage, the packing being held in place by the screw-cover 54. This casing 6 is suitably supported on the 95 frame of cylinder 1, the castings for all these members being properly related and inter-bolted or otherwise engaged with each other to give a firm and durable support. Inside the body of casing 6 is a cylindrical lining 100 sleeve 40, which has a lower series of horizontal ports 43 and an upper series of horizontal ports 44. The ports 43 open into a circular port 52 in wall of casing 6, which port 52 is in communication with a long 105 straight port 42 that runs through the wall of the valve casing and the cylinder and enters chamber 3^a in cylinder 1 on one side of piston 2. The ports 44 open into a circular port 51 in the wall of casing 6, which port 51 is in communication with the long 110 straight port 41 that runs through wall of the casing and cylinder and enters the chamber 3 in cylinder 1 on the side of piston 2 opposite to the chamber 3^a. Within casing 115 6 is an upper chamber 7, and a lower chamber 7^a. Within the stationary ported sleeve 40 is the vertically movable valve proper 47, which has a hollow interior chamber 48, and is made integral with a valve rod 9 that projects through the bearing on the lower casing head 55, and is connected with members 120 outside the valve mechanism for the operation of the latter. The interior chamber 7 of the casing 6 is in communication with the 125

interior of sleeve 40 and the interior bore 48 of valve 47, and the interior chamber 7 receives air or steam pressure through a central passage in the casing head 53 to which is coupled air or fluid pressure pipe 8, running from some source of fluid pressure. The interior space 48 of valve 47 is provided with ports 49 that open into chamber 7^a when valve 47 is in its lower position. 6 Further valve 47 is provided with a central portion of reduced outside diameter to furnish an annular port 50 around the valve and between it and the contiguous wall of the sleeve 40. Annular port 50 when the 10 valve is in its upper position connects ports 44 with a central exhaust port 45 in the sleeve 40, which port or ports delivers exhaust fluid pressure into an outlet pipe 46 that is screwed into the wall of casing 6. 15 And when the valve 47 is in its lower position as shown in Figure 9 the port 50 connects ports 43 with exhaust port 45. In one case the pressure in cylinder chamber 3 is exhausted to atmosphere after doing its 20 work; in the other case the pressure in cylinder chamber 3^a is exhausted to atmosphere after doing its work. It will be understood that valve 47 is of the balanced piston type, 25 between the pressure in the two chambers 30 7 and 7^a.

The receiver head B may have any desired form, size and shape, so that it may be convenient for disposing thereon and therewith many of the features of my invention. 35 Thus it has a protuberant front portion 35 surrounding a chamber which is a part of the receiver, see Figure 3, and connects therewith through an opening, which accommodates the movement of a rearwardly extending rod 39 which carries a float G so that as the float rises and falls due to the change of the water level it will move the rod 39 up and down. This rod 39 is connected to a short horizontal shaft 38 which is supported in bearings 37, 37, in the projecting member 35, see Figure 2, and the end of rod 39 is cleft or slotted at 33 to engage a horizontal pin 34 in the lower end of a vertical rod 10 carried in a vertical bearing 36 in the 45 front part of member 35. This rod 10 is aligned with the control valve stem 9, and is preferably fastened thereto by means of a pin 56 or some other device, so that the rods 9 and 10 may move in unison as a single 50 rod. By using a float for actuating the control valve, it will be noted that when the receiver A is entirely full of water the control valve 47 will be brought down by rod 39 and connecting rods 9 and 10 to its lower- 55 most position, as shown in Figure 9.

The essential features of the whole operation of the improved receiver pump will now be quite evident with a little further explanation. When the tank is full of water 60 and the float device has operated the control

valve by pulling it down the effect of such movement of the valve will be to uncover ports 44 and permit the air or other fluid pressure that fills chamber 7 from pipe 8 to pass through port 41 into cylinder chamber 3 on the left side of piston 2 and drive the latter towards the right, which will cause piston rod 4^a to rock bell crank lever 26 so that it will lift valve rod 15 of the steam supply valve, and also lift valve 13 70 from its seat 14 and permit high pressure steam to flow through the opening below valve 13 and immediately rush by way of port d into long port D and then through ports E and F into receiver A on top of the water which completely fills the same. At the same time that the piston rod 4^a rocks bell crank 26 to open the steam supply valve, the piston rod 4 will rock bell crank 26^a to force down valve rod 15^a and apply vent valve 13^a to its seat 14^a, so that at this moment there can be no venting of the steam, for obviously steam will also fill the long port C and the port c and chamber 19^a 80 and be in readiness to pass the valve edge 25^a the movement it is released from the valve seat 14^a, but of course as long as valve edge 25^a clamps down tight on seat 14^a steam can not vent through this valve. So long as the high pressure steam is acting 90 on the contents of the receiver A to expel the same the vent valve will remain tightly closed and the steam supply valve will remain fully open. But as soon as all the water has been expelled from receiver A 100 it is necessary to get rid of the steam therein so that it can again fill with water. While the water level in the receiver has been dropping the float has been dropping with it and this has been causing the control valve 47 to rise, and when the receiver is entirely empty and the float is on the bottom, the valve 47 will be in its top position, see Figure 2, when the port 41 and port 51 are connected through ports 44 and 105 annular port 50 with exhaust 46 to allow exhaust from cylinder chamber 3, while the pressure inside chamber 48 in valve 47 is allowed to pass through ports 49 and 110 ports 43 into circular port 52 and straight port 42 into cylinder chamber 3^a and cause a reverse movement of piston rods 4 and 4^a, 115 rocking the bell cranks 26 and 26^a reversely and closing the steam inlet port and opening the steam vent port, so that all the steam in 120 receiver A is promptly disposed of into the atmosphere. These operations progress regularly in automatic alternation.

In Figures 10 and 11 I have shown an alternative form of the pressure-control valve which admits pressure to the control cylinder 1 to act against piston 2. Figure 10 is a vertical section of this alternative form of pressure-control valve when in the tank-filling position; and Figure 11 is a 125

section of the same when in the discharging position.

There are cases where the condensate or other material which flows into the tank A moves very slowly or sluggishly, as it is heavy or thick or for some other cause has a slow movement, so that the valve 47^a has a correspondingly slow movement. This makes the movement of the float G unsteady, due to the agitation of the condensate in the receiver. If the pressure control valve were like that shown in Figures 1, 2, 8, and 9, where the valve rod 9 is rigidly attached to the valve body 47, the said valve 47 will open the ports 44 slightly, then close the same again, and this action will force piston 2 part of its travel, and when valve 47 closes ports 44 again the piston 2 will return to its former position, due to the pressure on its opposite side, if there is any leakage by piston 2.

So in order to overcome this objection to the working of the control valve I have devised an alternate form adapted for certain cases, and shown in Figures 10 and 11, and having as a leading feature a valve 47^a which is separated from its stem 9^a. This valve 47^a has a central passage 65 to loosely receive the upper section 64 of the valve stem 9^a, which section 64 has a top collar 62 provided with perforation 63, while the stem 9^a has the part adjacent to the lower end of section 64 provided with a fixed collar 61 provided with perforations 66. The valve body 47^a may be also provided with a number of small longitudinal passages adjacent to the valve stem section 64 for the flow of pressure.

In this modified or alternative form of the pressure-control valve, designed to meet special conditions, I employ the same casting 6, as before, containing fixed sleeve 40 with upper ports 44, entering circular port 51, which connects with straight port 41 running to cylinder 1 and delivering pressure on one side of the piston 2, and lower ports 43, and circular port 52 connecting with straight port 42 running to cylinder 1 and delivering on the other side of the piston 2, while there is the exhaust pipe 46, and exhaust port or ports 45 connected with the ports 43 at one time by annular port 60 on the outside of valve 47^a, said exhaust outlet being connected at another time with the ports 44 by the annular port 60.

The valve body 47^a is substantially like the valve body 47, in that it performs substantially the same functions, and is only modified as explained to allow the valve stem to be movably connected therewith, so that the stem of the valve will have a longer travel than the valve.

Below valve 47^a is the chamber 7^a, and above it is the chamber 7. During the movement of the valve stem 9^a and 64, it will

be seen that when it descends the top collar 62 will come into contact with top of valve 47^a and pull the valve down; and when the stem ascends the lower collar 61 will strike the bottom of valve 47^a and lift the same. 70 But the valve stem has a certain amount of free movement without engaging the valve so as to change its position.

The ports 63 in collar 62 allow pressure to pass from chamber 7, when collar 62 is 75 closed down on top of the valve, and then through passage 65 around stem 64 and out into the lower chamber 7^a; or if the lower collar 61 is closed against the bottom of the valve pressure can pass through the ports 80 66 from passage 65 into chamber 7^a.

Therefore it will be apparent that, in the operation with certain kinds of condensate or other liquids, if the float G in its upward travel during the filling operation, should, for instance, actuate the valve 47^a so as to open the ports 44, as in Figure 11, and then due to the agitation of the liquid, the float G should drop back slightly, it will not act upon the valve 47^a, as the stem 9^a is not 90 fixedly attached thereto; but the separable connection will allow the float to move back while the valve will stay in open position due to the clearance between collar 62 and valve 47^a, so that piston 2 will not be interfered with but will be allowed to make its full travel. A similar relative action of the valve stem will take place when the valve is in certain other positions, without interfering with the valve itself, and thus the piston 2 is allowed to follow its regular course to the end of its travel on each movement.

Thus I show two forms of the pressure-control valve which introduces pressure into 105 the cylinder 1 to move the piston therein one way or the other. Other forms may obviously be devised and used for the same purpose. In some cases a slide valve may be utilized. Hence I reserve the liberty of 110 varying and changing many of the details of my invention within the scope of the claims.

What I claim, is:

1. In an automatic receiver pump of the 115 class described, the combination of a liquid-holding tank having an inlet and outlet, a control cylinder and its piston, a buoyant member in the tank, a balanced piston pressure-control valve for said cylinder and piston, means whereby the buoyant member positively and automatically actuates said balanced piston pressure-control valve, means comprising a casing having ports running from the pressure-control valve to opposite ends of the cylinder whereby pressure may be supplied by the valve to opposite sides of the piston and exhausted therefrom, a sleeve in said casing having ports to permit pressure to pass into ports leading to the control 120 125 130

- cylinder, a steam inlet valve for the tank and a steam outlet valve for the tank, both controlling a common passage into the tank, and connections between the aforesaid control piston and the steam inlet and outlet valves, so that when the piston is actuated in one direction the inlet valve will be opened and the outlet valve closed, and when the piston is actuated in the opposite direction 10 the inlet valve will be closed and the outlet valve opened.
2. In an automatic receiver pump of the class described, the combination of a liquid holding tank having an inlet and outlet, 15 a control cylinder and its piston, a buoyant member in the tank, a balanced piston pressure-control valve-mechanism for said cylinder and piston, said valve mechanism comprising a casing having ports running to opposite ends of the control cylinder to supply pressure to opposite sides of the piston in said cylinder, and having also an exhaust outlet, a sleeve in said casing ported to permit pressure to pass into the ports 20 leading to the control cylinder, a hollow piston provided with an external annular port which at times connects the exhaust outlet with the ports leading to the control cylinder, and means for supplying pressure to chambers in said casing above and below the hollow piston so that it may pass through the sleeve ports and into the ports running to the control cylinder, means whereby the buoyant member positively and automatically actuates the piston member of the balanced piston pressure-control valve mechanism, a steam inlet valve for the tank 25 and a steam outlet valve for the tank, both controlling a common entrance into the tank, and connections between the aforesaid control piston and the steam inlet and outlet valves, so that when the piston is actuated in one direction the inlet valve will be opened and the outlet valve closed, and when the piston is actuated in the opposite direction the inlet valve will be closed and the outlet valve opened.
3. In an automatic receiver pump of the class described, the combination of a liquid holding tank having an inlet and outlet, a control cylinder and its piston, a buoyant member in the tank, a balanced piston pressure-control valve-mechanism for said cylinder and piston, said valve mechanism comprising a casing having ports running to opposite ends of the control cylinder to supply pressure to opposite sides of the piston in said cylinder, and having also an exhaust outlet together with circular ports merging into the ports leading to the control cylinder, a stationary sleeve held in said casing and having two series of ports entering the circular ports, a hollow piston movable up and down in the sleeve and open at the top and provided with ports near the bottom end, said piston having also an external annular port to connect the ports with the exhaust outlet, and having also a stem, means connecting the buoyant member with the said stem of the piston member so as to automatically move the same up and down, steam inlet and outlet valves for the tank, and connections between the same and the control piston in the control cylinder.
4. In an automatic receiver pump of the class described, the combination of a liquid holding tank having an inlet and outlet, a control cylinder and its piston, a buoyant member in the tank, a balanced piston pressure-control valve-mechanism for said cylinder and piston, said valve mechanism comprising a casing having ports running to opposite ends of the control cylinder to supply pressure to opposite sides of the piston, an exhaust outlet for said cylinder, a hollow inner piston member having an external annular port and provided with a stem, means connecting the buoyant member with said stem, steam inlet and outlet valves for the tank, the same having stems, bell-crank levers actuated by the control piston rods and engaging the steam valves for positive movement.

6. In an automatic receiver pump of the class described, the combination of a liquid holding tank having an inlet and outlet, a control piston and cylinder, the piston being provided with rods extending in opposite directions, a buoyant member in the tank, a balanced piston pressure-control valve mechanism for said cylinder and piston to deliver pressure to opposite sides of the piston and 10 exhaust if therefrom, means connecting the buoyant member with said valve mechanism, steam inlet and outlet valves for the tank controlling a common opening into the tank, slotted valve stems for said valves, said 15 stems being provided with yielding pins, and bell crank levers pivotally supported in the tank and having one arm engaging one of the control piston rods and the other arm engaging the slot in the valve stem and 20 working against the yielding pin in closing the valve so as to properly seat the same.
7. In an automatic receiver pump of the class described, the combination of a liquid holding tank having an inlet and outlet, a 25 head for said tank provided with a pair of ports merging together at a common opening into the tank, one port being for high pressure steam and the other for exhaust steam, a steam valve arranged to deliver steam to its 30 port, a vent valve arranged to receive steam from its port, a control cylinder and its piston therein, the latter having oppositely-projecting piston rods, connections between said rods and the steam and vent valves so that 35 the movement of the piston one way or the other may impart a joint movement to the valves, opening one simultaneously with closing the other, a balanced piston pressure control valve for delivering pressure to opposite sides of the control piston, an exhaust 40 outlet for the control cylinder, a float in the tank, and connections between the float and the valve whereby the latter is automatically actuated.
8. In an automatic receiver pump of the class described, the combination of a liquid holding tank having an inlet and outlet, a head for said tank having a pair of ports merging together at a common opening into the tank, one port being to convey steam to the tank and the other being to vent it from the tank, a steam valve arranged to deliver live steam to the port through an inlet port, a vent valve arranged to allow steam to vent 50 from its port through an outlet port, a control cylinder and its piston therein, the latter having opposite piston rods, connections between said rods and the steam and vent valves, including bell crank levers and valve stems all interpivoted with the piston rods for joint operation, a balanced piston pressure control valve for delivering pressure to opposite sides of the control and exhausting it therefrom, a float in the tank, and means 55 connecting the float and the pressure control valve.
9. In an automatic receiver pump of the class described, the combination of a liquid holding tank, having an inlet and an outlet, a control cylinder and its piston, the latter having opposite rods, a main control valve for admitting pressure to move the control piston one way or the other, an exhaust outlet for the control cylinder, a float in the tank, means connecting the float with the main 60 control valve to actuate the same, a steam valve for admitting high pressure steam to the tank, a vent valve for disposing of the steam after doing its work in the tank, said valves each having a casing, a valve rod provided with a relief valve member thereon and also having a winged section supporting centrally a loose main valve member which controls a seat, and connections whereby the 65 said valves are positively actuated by the movement of the control piston.
10. In an automatic receiver pump of the class described, the combination of a liquid holding tank, having an inlet and an outlet, a control cylinder and its piston, the latter having opposite rods, a main control valve for admitting pressure to move the control piston one way or the other, an exhaust outlet for the control cylinder, a float in the tank, means connecting the float with the main 70 control valve to reciprocate same, a steam valve for live steam controlling a port to the tank, a vent valve for exhausting steam and controlling a port from the tank, both of said ports being in communication with each other and with the same entrance into the tank, said valves each having a casing, a valve rod having an outwardly projecting slotted end and being provided within the 75 casing with a relief valve member and also a winged section passing centrally through a loose main valve member which controls a main seat, said main valve member and the relief valve having a range of relative movement, and connections between the valve rods and the control piston rods consisting of pivoted bell crank levers pivotally connected to the piston rods and loosely engaging the slotted ends of the valve rods, so the steam and vent valves may be positively actuated 80 by the movement of the control piston.
11. In an automatic receiver pump, the combination of a liquid holding tank having an inlet and outlet, a control cylinder and its piston, the latter provided with rods extending in opposite directions, a buoyant member in the tank, a pressure-control valve mechanism for said cylinder and piston, comprising a casing having ports running to opposite ends of the control cylinder to supply pressure to opposite sides of the piston, an exhaust outlet for said control cylinder, a piston member having an external annular 85

port and a central passage and a stem, passing loosely through said valve and provided with a perforated collar above the valve and another below the valve, so that the valve and its stem may have a relative play, means connecting the buoyant member with said stem, steam inlet and outlet valves for the tank, the same having stems, bell-crank levers actuated by the control piston rods 10 and engaging the steam valves for positive movement.

12. In an automatic receiver pump of the class described, the combination of a liquid holding tank having an inlet and outlet, a head for said tank provided with a pair of ports merging together at a common opening into the tank, one port being for high pressure steam and the other for exhaust steam, a steam valve arranged to deliver steam to its port, a vent valve arranged to receive steam from its port, a control cylinder and its piston therein, the latter having oppositely-projecting piston rods, connections between said rods and the steam and vent valves so 25 that the movement of the piston one way or the other may impart a joint movement to the valves, opening one simultaneously with closing the other, a balanced piston pressure control valve for delivering pressure to opposite sides of the control piston, an exhaust outlet for the control cylinder said valve including a piston member proper and a stem loosely connected therewith and having a longer travel than the piston member, a float 35 in the tank, and connections between the float and the valve whereby the latter is automatically actuated.

13. In an automatic receiver pump of the class described, the combination of a liquid holding tank having an inlet and outlet, a head for said tank having a pair of ports merging together at a common opening into the tank, one port being to convey steam to the tank and the other being to vent it from 45 the tank, a steam valve arranged to deliver live steam to the port through an inlet port, a vent valve arranged to allow steam to vent from its port through an outlet port, a con-

trol cylinder and its piston therein, the latter having opposite piston rods, connections between said rods and the steam and vent valves, including bell crank levers and valve stems all interpivoted with the piston rods for joint operation, a balanced piston pressure control valve for delivering pressure to opposite sides of the control and exhausting it therefrom, said control valve including a piston member having an annular port and a central passage, and a stem loose in said passage and provided with perforated collars 60 above and below the piston member, a float in the tank, and means connecting the float and the pressure control valve.

14. In an automatic receiver pump of the class described, the combination of a liquid holding tank having an inlet and outlet, a control cylinder and its piston, a buoyant member in the tank, a balanced piston pressure-control valve for said cylinder and piston, said valve having a piston member provided with an annular port and a central passage, and a valve stem passing loosely through said piston member and provided with perforated collars above and below said piston member, said stem having more travel 70 than the piston member, means whereby the buoyant member positively and automatically actuates said balanced piston pressure-control valve, means running from the pressure-control valve to the opposite ends of the cylinder whereby pressure may be supplied by the valve to opposite sides of the piston and exhausted therefrom, a steam inlet valve for the tank and a steam outlet valve for the tank, both controlling a common passage into the tank, and connections between the aforesaid control piston and the steam inlet and outlet valves, so that when the piston is actuated in one direction the inlet valve will be opened and the outlet valve closed, 80 and when the piston is actuated in the opposite direction the inlet valve will be closed and the outlet valve opened.

In testimony whereof I hereunto affix my signature.

HOWARD G. SHORTT.
